UNITED STATES PATENT OFFICE

ALBERT H. SHEFFIELD, OF KANSAS CITY, KANSAS

TERRA-COTTA-FIRING SYSTEM

Application filed April 15, 1927. Serial No. 183,948.

This invention relates to the firing of terra cotta kilns, and has for its primary object, the provision of a novelly constructed system for the firing of open kilns of any size or capacity.

Heretofore, it is well known, that kilns used in the firing of terra cotta have been essentially equipped with a muffle, which required replacement, which was expensive to keep up, and which oftentimes was leaky, resulting in the ruining of a kiln of ware, and which required additional fuel to heat the same, and additional time in cooling after the ware had been burned.

Accordingly, one of the principal objects of the instant invention is to provide a simply constructed kiln, which is comparatively inexpensive, much more efficient to operate, and which performs the required duty even better than the old ordinary kiln heretofore used.

An even further object of this invention is the provision of a kiln for the firing of terra cotta which does not include the well known fire brick muffle, and which may be operated at a decided saving with respect to the time and labor required.

Another object of this invention is the provision of a new combination of gas burning appliances, which are novelly arranged to co-operate with the new type of kiln in such a manner that the entire burning system is extremely desirable, easy to operate, not likely to get out of order, and performs a more thoro piece of work at a decided saving.

Minor objects of this invention will appear during the course of the detailed specification referring to the accompanying drawings, wherein

Figure 1, is a side elevation of a terra cotta firing kiln, and system made in accordance with this invention.

Fig. 2, is a horizontal cross-section of the same, taken on line II—II of Fig. 1.

Fig. 3, is a vertical central section taken thru the kiln on line III—III of Fig. 2.

Fig. 4, is an enlarged longitudinal central section, taken thru the restricted throat and mixing chamber.

Fig. 5, is a fragmentary sectional view

showing the window tube, thru which the ware may be observed, and

Fig. 6, is a vertical central section thru a modified form of kiln construction.

Similar reference characters refer to like parts thruout the several views, and the numeral 7 designates the side walls of the round type, which when constructed in accordance with this invention, has a top 8, which terminates in a central stack 9, and which has a bag wall 10 extending around the inner chamber, and spaced apart from wall 7 by any suitable spacing element 12, to form an annular chamber which is in communication with a plurality of openings 13, extending thru wall 7.

It is notable that this kiln construction does not include a muffle wall which will burn out often, and cause other troubles well known in the art. A heat measuring device 14, of any suitable character may be used in connection with the kiln, and the ware to be burned may be stacked in the well known fashion to completely fill the kiln prior to firing. In firing terra cotta with a system contemplated by this invention, the products of combustion are allowed to come in direct contact with the ware, and the system shown utilizes gas for a fuel. In constructing a kiln, an air line 15 should lead from any suitable compressor and surround the kiln at a point above openings 13. A single gas main 16 may be used to supply all of the burners, and since each burner is feeding a flame in the kiln thru an opening 13, but one will be here fully described. The gas flowing from main 16 thru the lead-in 17, enters governor 18, where it is reduced to zero pressure. From this point the gas is pulled in by the energy furnished by the pressure of the air which enters the throat 19 from a conduit 20, leading from the main air line 15. The amount of air passing thru the conduit 20 to throat 19 may be controlled by any suitable air cock 21, and as it passes thru the restricted throat 22, the gas which flows from governor 18, thru pipe 23 is drawn in thru perforations 24 at a point where the air passing thru the restricted throat reaches velocity head. Immediately after the air and

gas meet at this restricted point, they pass to the expansion cone 25, where they are changed back to static head again, where they are thoroly intermixed, and the mixture automatically converted to a pressure head, suitable for delivery to the burners thru pipe connection 27. The amount of gas allowed to enter may be controlled by a valve not here shown, and the mixture is ignited at the burner nozzle 28, positioned inside of the opening 13. Combustion takes place at the end of burner nozzle 28, and the fire is diverted upwardly by bag wall 10, which should terminate at a height equal to approximately one third the height of the kiln. As shown in Figure 2, this bag wall extends completely around the kiln, and the equal distribution of the plurality of burners around the kiln insures even temperature. In the form shown in Fig. 6, the construction illustrated is desirable only when large kilns are being constructed, and it is desired to convey some of the heat to the center where some of the heat from the burners may pass thru tunnels 29 to the center of the floor, which will help mature the ware in the center of the kiln. Also, in large kilns, an additional inner stack 30 is constructed, leading to the central stack 9. The bottom of stack 30 may have a large number of openings 31, thru which the flue gases will escape after having risen over the bag wall to the crown of the kiln, and thence down to the floor again.

It is plain to be seen, that this method of open firing is a departure from the established practice, and since the time of burning is cut in half, and since the rate of cooling is more rapid, the system is extremely desirable. It has been found that the ware burned in these kilns does not crack, and it is obvious that the removal of muffle walls, additional stacks and the like, will greatly increase the capacity of every kiln. It is also notable that kilns now in use may be supplied with systems of this character. Heretofore, the use of coal or like fuel has caused the replacement of all inner wall constructions, and since the gas has no deteriorating effect on fire brick, a cheaper grade of brick can be used in the construction of bag wall and kiln walls proper. In operating the kilns, it is advisable to open all of the draught regulating appliances to allow free circulation and to light but a few of the burners at first, in order that the temperature may be brought up gradually, at the same time allowing a great amount of secondary air to pass in opening 18, and into the kiln, as the kiln rises in temperature, additional burners may be lit and turned low until about the sixth hour, when the full number of burners may be lit and, if the bottom of the kiln is lagging behind, the dampers may be closed a small amount, which will put pressure on the top of the kiln to force the heat to the bottom. Experience

has determined the fact that carbon in the clay is oxidized at about 1350 degrees F. and up to this point the operator should be careful not to close the damper too much. After the kiln has reached this point, it has been found that the same may be run under pressure if desired.

Manifestly, the novel points of this system are extremely important, and valuable in the art. It is understood that various modifications may be made without departing from the spirit of the invention, and having thus described the preferred embodiment of a terra cotta burning system, what is claimed as new and desired to be secured by Letters Patent is:

1. In a terra cotta firing system, a kiln having a continuous side wall, and an entirely closed bottom a relatively low bag wall extending around the inside of said kiln to form a continuous space between said side wall and bag wall a continuous bottom between said side wall and bag wall substantially in the plane of the bottom of said kiln and a plurality of openings extending thru said side wall and communicating with said continuous space.

2. In a terra cotta firing system a kiln having a continuous side wall, a relatively low bag wall extending around the inside of said kiln to form a continuous space between said side wall and bag wall, a plurality of openings through said side wall and communicating with said continuous space, an entirely substantially horizontal closed bottom for said kiln extending to the side wall, a stack communicating with the top of said kiln, a gas burner adjacent each of said side wall openings and an air supply and gas supply main common to all of said burners.

In testimony whereof, I hereunto affix my signature.

ALBERT H. SHEFFIELD.
